GAMING DEVICE

William Steig, New York, N. Y.

Application March 15, 1951, Serial No. 14,503

Term of patent 14 years

(Cl. D34—5)

To all whom it may concern:

Be it known that I, William Steig, a citizen of the United States and resident of New York, in the county of New York, State of New York, have invented a new, original, and ornamental Design for a Gaming Device, of which the following is a specification, reference being had to the accompanying drawing, forming a part thereof, and of which

Fig. 1 is a side elevational view of a gaming device, showing my new design.

Fig. 2 is a side elevational view thereof in inverted position with respect to Fig. 1, showing one arrangement of balls of contrasting colors.

Fig. 3 is a bottom plan view thereof, showing one of the contrastingly colored balls, and

Fig. 4 is a top plan view thereof.

The figures are lined to indicate transparency, and the balls are shaded to indicate color contrast.

I claim:

The ornamental design for a gaming device, as shown and described.

WILLIAM STEIG.
